UNITED STATES PATENT OFFICE.

JONATHAN HUNSGERGER, OF SKIPACK, PENNSYLVANIA.

IMPROVEMENT IN WASHING-MACHINES.

Specification forming part of Letters Patent No. 129,031, dated July 16, 1872.

Specification describing a new and Improved Washing-Machine invented by JONATHAN HUNSGERGER, of Skippack, in the county of Montgomery and State of Pennsylvania.

My invention consists of the peculiar construction of the dash-board and relative arrangement of the brake for working the movable one with it and the case, all as hereinafter described.

Figure 1 is a sectional elevation of a washing-machine constructed according to my improvements, the section being taken on the line *x x* of Fig. 2; and Fig. 2 is a sectional elevation of the same, taken on the line *y y* of Fig. 1.

Similar letters of reference indicate corresponding parts.

A is a case, B a fixed board, and C a swinging board or dasher, arranged in a manner similar to some machines heretofore made. My improvement in the said boards consists of the vertical ribs D on the fixed board, and E on the movable board, with blunt sharp edges, arranged in the order indicated in Fig. 2, in which the movable board is turned bottom side up on its supporting-rod, the said order being so that the ribs on one board come in the middle of the spaces on the other board. Commonly these boards have been made with only the longitudinal ribs. I have found by practical tests that these vertical ribs increase the efficiency of machines of this character.

I pivot the brake or levers G to the machine at H instead of on the upper ends of posts fixed on the frame to rise considerably above it, as heretofore arranged, and I connect them to the board C by the cross-bars J K, and a rod, I, in such manner that the free ends rise up at the front side of the machine properly for the application of the power. This plan simplifies the cost considerably, and the arrangement is preferable, because the swinging of the brakes upward and backward to raise the board C out of the machine can be done easier and better than when arranged in the old way.

Having thus described my invention, I claim as new and desire to secure by Letters Patent—

The swinging board C and the fixed board B, provided respectively with vertical wedge-shaped ribs E and D, so arranged that the ribs of one board enter the spaces between the ribs of the other, in combination with the rod I, cross-bar J K, and brakes G G, all arranged as set forth.

JONATHAN HUNSGERGER.
